DEVELOPING DEVICE

Fred Doetzel, Jr., Cedar Rapids, Iowa

Application June 22, 1936, Serial No. 86,478

16 Claims. (CL 95—94)

My invention relates to the art of printing by the photographic method and has particular relation to a device for developing and washing photographic prints such as blue prints, photo-copies, Van Dyke prints, and the like.

In the art of printing by the photographic process it is customary to expose a sensitized film, upon which an original or positive print is superposed, to light rays and thus alter the chemical condition of the sensitized film according to the degree or amount of light which filters through the original and strikes the film. In order to carry out the chemical change to completion it is necessary to wash the sensitized film in

certain suitable chemical baths and to wash the chemical solution from the film. After the process has been completed the film is dried, in commercial work, by mechanical means such as heaters or blowers or both.

This printing process is usually accomplished by means of a machine which utilizes a continuous strip of sensitized film and which leads the strip into the various baths and over a dryer. This process is quite satisfactory where the operator has a large number of positive prints so that he may cover practically the entire sheet of sensitized film and thus prevent wastage. However, if the operator has only a few positives to work from he cannot cover the strip, and since the strip in the machine is several feet long he may waste six to eight square feet of film in order to obtain one square foot of printed film.

I have conceived of a printing machine which obviates these difficulties and which will wash and develop individual strips or pieces of sensitized film. The machine has been materially improved in structure and changing of the baths is readily and quickly accomplished by means of motor driven devices.

A general object of my invention is to provide a device which will wash and develop individual strips or pieces of film, sheets, paper and the like.

An important object of my invention is to provide a device of the general character above noted in which the sheets are fed to the machine and carried through the machine by carrying means, the contact area of which is very limited, so that adhesion of the sheets to the various carrying means is almost entirely eliminated.

Another object of my invention is to provide means whereby the print may be treated while being carried on the carrying means, rather than in the intervals between the contacting periods of the carrying means.

Another object of my invention is to provide

an improved feeding means for feeding prints into the machine of the above character.

Another object of my invention is to provide a new means of limiting the amount of moisture or solution carried over from one bath to another. 5

Another object of my invention is to provide a new and improved means for applying chemical to the print and for removing it from the print and keeping it from passing on to the next bath.

Another object of my invention is to provide a 10 new and improved means for removing a print from a roller during the developing process.

An important feature of my invention is that no mechanical means is employed, such as fingers and the like, during the intermediate steps of 15 the developing process, for removing the prints from the various rollers.

Other and further features and objects of the invention will be more apparent to those skilled in the art upon a consideration of the accompanying drawings and following specification, wherein is disclosed a single exemplary embodiment of the invention, with the understanding, however, that such changes may be made therein as fall within the scope of the appended claims. 20 25 without departing from the spirit of the invention.

In said drawings:

Figure 1 is a schematic diagram of a device constructed according to one embodiment of my 30 invention.

Figure 2 is an end elevational view corresponding in general with Figure 1 and taken from the right of the machine when viewed from the feeding and receiving side of the machine which is 35 considered as the front.

Figure 3 is also an end elevational view of the machine but is taken from the opposite end from Figures 1 and 2 on the left end.

Figure 4 is a front elevational view of the ma- 40 chine.

Figure 5 is a rear elevational view of the ma- chine, and

Figure 6 is a fragmentary view in perspective of the carrying means for carrying prints from 45 the feed table into the machine.

Referring now to the drawings and more particularly to Figures 1 and 6, a print which has been previously exposed and printed is fed into the machine from the feed table 10. A roller 50 11 is provided just back of the feed table, and this roller has grooves 18 in the surface thereof to permit ends of carrying means, such as wires 12, which are secured to a plate 20, to be received within the grooves. A plurality of disks 55

13 are rotatably mounted above the roller 11 and these disks are so spaced from the roller that a print inserted with its edge against the disks and roller will be drawn into the machine 5 through rotation of the disks and roller, these parts being rotated by mechanism hereinafter described. The print is then driven across the upper surfaces of the wires 12 by means of the disks and roller until the leading edge reaches 10 the large roller 16. During the period that the print is being carried from the feed rollers 11 and 13, water is being sprayed upon the surface of the print from the spray pipes 17 and 17a whereby the upper surface of the print is wetted 15 and the unexposed portions of the print are washed and the first step of the usual chemical change or process is accomplished. The wires slope slightly upward whereby the wash water tends to run down over the print and form a 20 puddle on the print adjacent the disks 13 to insure the wash water covering the print.

A relatively smaller roller 18, which may be termed a squeegee roller, is positioned above the large roller 16 and the surface of this roller 25 rolls upon the surface of the roller 11 and effects a closer adhesion of the print to the large roller 16, as well as removing surplus moisture from 30 the surface of the print. A squeegee strip 19 is positioned just below the wires 12 in such position that it rubs on the surface of the roller 16 before it reaches the prints which are passing onto the roller and this squeegee serves the 35 double purpose of preventing moisture from the sprays 17 and 17a from running down to the lower portion of the roller 16 and also prevents carrying an excess amount of water from a stripping spray, hereinafter described, up on the roller 16, although sufficient water is deposited on the roller to cause the print to adhere to the 40 roller. This portion of the process must be closely regulated so that too much moisture is not carried up on the roller because to do so would dilute the chemical bath. Just after the print has passed beneath the roller 18, spray 45 pipe 21 and 21a deposit or spray developing and fixing chemical on the print to carry out the second step of the developing process. The chemical runs on down over the surface of the print and roller until it reaches a combined 50 squeegee and puddle roller 22. The surface of the roller 22 is of relatively soft resilient material such as molletin, flannel, or the like. This roller not only serves to remove the chemical from the face of the print and from the large 55 roller 16 but also serves to cause a puddle of chemical to collect between the two rollers 22 and 16 to insure the chemical reaching all parts of the print.

After the print has passed between the rollers 60 16 and 22, it is carried on down under the roller and may start up the other side, but at the lowest point a spray of water from the spray pipe 65 23 strikes between the advancing print and the roller 16 to wash the print from the roller and cause it, through its own weight, to drop down as it advances, until it strikes the roller 24, which is rotating in the opposite direction from roller 18.

The spray 23 is not only a means of removing 70 the print from the roller 16 but also acts to wash the inner face of the print, to moisten the surface of the print, and also remove any trace of chemical which might possibly have been deposited on this inner face of the print. A trough 75 26 is provided beneath the squeegee roller 22, and

a lip 27 of this trough extends up under the roller 22 to a position between the rollers 16 and 22 in order that chemical, which is being carried around the squeegee roller or any excess chemical dripping from the roller is carried down into the tank 28 where it may be recirculated back to the sprays 21 and 21a. 5

The prints, as they drop from the roller 16, engage themselves, by adhesion, to the roller 24 and are carried around in front of and below this 10 roller to a position adjacent the roller 26 and possibly slightly beyond the closest point between the two rollers. At this position the water spray from a spray pipe 29 strikes between the advancing print and the roller 24 and peels the 15 print from the roller. The spray acts not only as a means of removing the print from the roller 24 but acts also as a water wash to wash the face of the print which may not have been previously washed because it had not been exposed 20 to the previous spray 23. The spray 23 strikes only the back of the print and thus the spray 29 is desirable to wash the front of the print. The purpose of these two sprays 29 and 23 is to remove all vestige of chemicals which may have 25 adhered to the print and to thus complete the final or washing step of the developing process.

Any excess water from the sprays 23 and 29 is prevented from rolling down the front or advancing side of the roller 26 by means of a squeegee strip 31. A combined puddle and squeegee roller 32 is positioned to roll on roller 26 at the lower rear of the roller. The roller 32, like the roller 22, serves not only to remove excess moisture from the print but also as a puddling roller to insure moisture reaching all points on the print. 35

The print is then carried on around beneath the roller 26 where it passes between the roller 28 and another squeegee roller 33, this last named 40 roller 33 insuring complete squeegeeing of the print. The print is now in a moist condition but all excess moisture has been removed therefrom. Inasmuch as it is desirable to remove the prints from the machine in this semi-dry condition, I 45 employ another means for removing the prints from the roller at this point, this means comprising a series of roughly triangular shaped strippers 34. These strippers are provided with pointed portions 34a which readily pass between the 50 print and the roller 28 to remove the prints from the roller. The prints are sufficiently stiff that they pass along the under edges of strippers 34 and are deposited on the endless belts 36 which removes them from the machine. The belts 36 55 are rotatably supported on belt rollers 37 and 38. The belt roller 38 is mounted on the front of the machine and prints leaving the belts drop into a receiving trough 39 on the front of the machine.

Wash water from sprays 17 and 17a is caught 60 by the squeegee strip 19 and splash guard 41 and is carried into a waste water trough 42. The waste water from trough 42 is carried off by means of a conduit 43 down into a large tank 44. The water deposited in the tank 44 drains downwardly through drain pipe 46 into a circulating pump 47 (Figure 4), later more particularly described, which pumps the water back through flexible tubing 50 (Figure 4) to the spray pipes 17 65 and 17a, 23 and 29. The overflow of water from tank 44 is carried off to the sewer by means of overflow pipe 48. Water is supplied from the city mains to the tank 44 by means of a supply line 49. In this manner a supply of fresh water is 70 75

being constantly added to the wash water insuring relatively clean water at all times.

The developing and fixing chemical in trough 26 is drained off by means of pipe 51 into a chemical tank 52 positioned below water tank 44. The chemical in tank 52 drains off through drain pipe 53 into the circulating pump 54 and from there is recirculated into chemical sprays 21 and 21a by means of flexible tubing 56 (Figure 4). The circulating pumps are driven by means of a prime mover such as the motor 57.

It is very desirable and in fact an important feature of my invention that the entire developing machine be encompassed in a relatively small space and it is by means of my connections and principles of operation that it is possible to mount the entire mechanism in a frame which may occupy a floor space the longest dimension of which is only a trifle greater than the width of the prints the machine is to develop and the width of which may be roughly four to five times the diameter of the largest rollers.

It is obvious that the parts of a machine embodying my invention, rotating and stationary, may be supported in any suitable manner as by plates or a fabricated framework or the like. The present embodiment of my invention, however, is mounted on and supported in a fabricated frame such as shown in the drawings. This frame includes vertically extending corner members 61, 62, 63 and 64 joined at the ends, top and bottom by cross members 66 and 67, 68 and 69, and at the front and rear by cross members 71 and 72, 73 and 74, respectively.

The spray pipes 17 and 17a are supported on straps 76 and 77 which are in turn supported from the top, front and rear cross members 71 and 73. These spray pipes are merely pipes having a series of small openings along the bottom thereof and the spray pipes may be readily removed for cleaning by detaching the clamps 78 and 79 by which they are clamped to straps 76 and 77. The spray pipes 21 and 21a are supported by brackets 70 which are parts of straps 76 and 77.

The rollers 11, 13, 18 and 16 are rotatably mounted in and supported from plates 81 and 82 which are secured across the ends of the machine. The roller 22 is supported for rotation by means of brackets 83 which are in turn mounted on plates 81 and 82. The squeegee 19 is also supported by means of plates 81 and 82. The squeegee 19 and carrying means 12 are also supported by plates 81 and 82. The splash guard 41 is supported by the feed table 10 and the feed table is mounted on vertical members 61 and 64.

The roller 24 is rotatably mounted on plates 84 and 86 and the plates 84 and 86 also support the spray pipes 29.

The roller 28 is rotatably mounted in end plates 87 and 88 and the plates 87 and 88 also support brackets 91, 91 and 92 in which rollers 37, 33 and 32 are rotatably mounted. The brackets 83, 89 and 92 are loosely engaged to the respective end plates so that the weight of the respective rollers holds them in place against the large rollers and the roller 33 in brackets 91 is biased against the roller 28 by means of a spring 93.

The strippers 34 and the squeegee strips 31 are supported in a sub-assembly by means of bracket 94 which in turn is supported by end plates 87 and 88. The spray 23 is supported by a bracket 95 which, in turn, is supported by plates 81 and 82.

The large rollers 18, 24 and 28, the feed roller

11 and the delivery roller 38 are power driven, the remaining rollers being rotated either through rolling on the power driven rollers or in the case of the roller 37, by means of belts 36. The power for rotating these rollers is furnished by a gear reduction drive motor 96 mounted on upright member 63. The motor 96, through the agency of the reduction gearing 97, drives an endless belt 98 which, in turn, drives a pulley 99 mounted on the shaft 101 of roller 28, at the right end of the 10 roller.

The large rollers 24 and 16 are driven through the agency of a train of gears 102, 103 and 104 which gear train is at the left end of the machine with the gears mounted on projecting shaft ends 101, 106 and 107 of respective rollers 28, 24 and 16. The delivery roller 38 is driven by means of a belt drive 108 from a pulley 108 on the shaft 106 of roller 24, the pulley 111 on roller 38 serving as the drive pulley for that roller.

The feed roller 11 is driven by means of a driven pulley 112, belt 113 and drive pulley 114, the drive pulley being mounted on shaft 107 of roller 16.

The water tank 44 is supported by cross members 116 and 117 and thus additionally stiffens 23 the structure. The chemical tank 52 is likewise supported in the vertically extending frame members 61, 62, 63 and 64 below the water tank. The pump assembly, including motor 57 and centrifugal pumps 47 and 54, is supported beneath the 30 chemical tank 52 by means of a platform 118, which is in turn supported by cross members 72 and 74.

The current for energizing motors 57 and 96 is controlled by switches 121 and 122, respectively. 25

In operation of the machine the exposed prints are fed in one by one to the rollers 11 and 13 and are carried through the first wash water to remove the unexposed portions of the print. Only the sensitized side of the print is washed at this 40 first operation and this sensitized face is immediately exposed to the chemical sprays from pipes 21 and 21a. The roller 22 acts to puddle the chemical over the sensitized face of the print and insure the chemical reaching all points on 45 this face. The print is then carried on down where the back side of the print is washed and then the front or sensitized side of the print is washed. The excess water is squeezed off by means of the rollers 32 and 33 and the semi-dry 50 print is stripped from the roller 28 by means of the strippers 34. The print falls on the belt 36 and is then carried out of the machine and into the catch tray 39. It is to be noted that in carrying the print to the first roller, advantage is 55 taken of the stiffness of the print to drive it into this roller. From this point on the print is stripped from successive rollers by water sprays without the necessity of intervention of other mechanical devices. When the print is removed 60 from the last roller the point of removal is such that the weight of the print assists in removing it from the roller. The print is now in a semi-dry condition and, of course, water sprays can not be used at this point, but I take advantage of 65 gravity to facilitate this final stripping operation.

It is apparent that I have eliminated the necessity for large wash tanks and chemical tanks by carrying on the successive steps of developing a print on rollers and by means of spraying and puddling device. I have likewise eliminated the necessity for carrying means such as belts and the like for carrying the prints between successive points in the machine. A developing machine constructed according to my invention has 75

met marked success and produces high quality prints completely washed and developed and without bleeding of the surplus coating into the white portions of the print. The prints are delivered in a semi-dry condition and may be quickly and readily dried without wrinkling or creasing, and the prints may be dried either by mechanical means or by air drying. As has been previously stated, this machine occupies a very small floor space, yet is capable of handling a large number of prints in a short time. It thus lends itself readily to the production of small prints and sheets which cannot be handled in the continuous blueprint machines known to the art. The width of the print is a direct factor of the width of the machine and the machine need be but very little wider than the print to be developed by it. The machine will handle not only small prints, but will develop prints from a roll almost any length. If desired, the printing machine might readily be used in connection with a continuous printing machine and the continuous strip of paper from the continuous printer may be led directly into the developing machine.

Another advantage and feature of my invention is that by using wetted or water retaining rollers the wash water and chemical is applied to both faces of the sensitized film or print at the same time. This permits wetting of the film on both sides at the same time and the film is thus permitted to stretch or expand on both sides because water is entering the film from both sides. This method also greatly assists in handling small prints.

Furthermore, my process avoids a marked difficulty of the devices of the prior art. The prior art devices employed belts and other mechanical means for carrying the sensitized films through the machine. These mechanical devices did not readily permit expansion of the film which was expanded by the action of water and consequently the film became creased and wrinkled. With machines constructed according to my invention the film passes freely from one roller to another and may readily expand, and the spaces between the rollers permit the film to stretch. This point is of major importance.

It is apparent that modifications of my invention may be made by those skilled in the art. For instance, a plurality of chemical and water sprays or single sprays may be used. The arrangement of squeegees and squeegee rollers, puddling rollers, and the like, may be modified. These and other modifications may be made without departing from the spirit and scope of my invention as set forth in the appended claims.

I claim as my invention:

1. In a print developing machine, at least two rollers positioned on horizontal axes one below another, and means for stripping the prints from the first of the rollers comprising means for producing a water spray the spray being directed between the advancing print and the roller, and the spray being located below the axis of the first roller so that when the print is stripped from the first roller it falls by gravity onto the second roller.

2. In a machine for developing sensitized film, means for propelling the film through the machine comprising rollers, means for holding the film while it is being treated including wetted rollers, and means for stripping the film from the wetted roller comprising means for producing a water spray the spray producing means being

located outside the rollers and the spray being directed between the advancing print and the roller.

3. In a continuous process print washing and developing machine, means for applying a chemical solution to the print including spray means and rollers for feeding the print through the machine and by the spray means, means for retaining excess chemical and recirculating it to the spray means including a squeegee roller. means for washing the print before applying the chemical including sprays, other means for washing the print after the chemical has been applied including another spray, including means for carrying off excess water and recirculating the same.

4. The combination, in a continuous process print washing and developing machine, of a conveying system including a series of spaced rollers arranged in close juxtaposition in a vertical plane so that a print will be conveyed through the machine by the combined action of gravity and sprays, spray devices for depositing chemical on the print at one portion of its travel through the machine, other spray devices for washing the print at points preceding and succeeding the point where the print was chemically treated, and means associated with the machine whereby excess chemical deposited by the spray devices is retained and recirculated to the spray devices.

5. In a print washing and developing machine, a plurality of rollers so disposed in a vertical plane that a print may be conveyed through the machine and subjected to washing and developing action solely by the action of gravity and sprays, spray devices for washing and for depositing chemical on the print at various points in its travel, other means for retaining and recirculating to the spray devices the excess water or chemical.

6. In a print washing and developing machine, a system of conveying and squeegee rollers arranged in close juxtaposition in a vertical plane for handling the print as it is exposed to chemical and washing action, the rollers being arranged in a vertical plane to permit the print to fall or from one roller to another by the action of gravity and spray means, other means for conveying the prints to and from the said system, spray devices located at various points along the line of travel of the print for depositing water and chemical solution on the print, means for driving the rollers and other means for circulating the washing water and chemical solution for expulsion from the spray devices.

7. In a print washing and developing machine, a first roller, means for placing a print on the first roller, sprays for spraying chemical on the sensitized face of the print while it is in position on the first roller, means for stripping the print from the roller including a water spray, the water spray being directed between the advancing print and the roller to wash the back side of the print, a second roller for receiving the print stripped from the first roller, and a wash spray for stripping the print from the second roller and for washing the sensitized face of the print.

8. In a print washing and developing machine, a first roller, means for placing a print on the first roller, sprays for spraying chemical on the sensitized face of the print while it is in position on the first roller, means for stripping the print from the roller including a water spray,

- the water spray being directed between the advancing print and the roller to wash the back side of the print, a second roller for receiving the print stripped from the first roller, a wash spray for stripping the print from the second roller and for washing the sensitized face of the print, a third roller for receiving the print stripped from the second roller, and squeegee rollers positioned to roll on the roller and print to squeegee water from the print.
9. In a print washing and developing machine, a first roller, means for placing a print on the first roller, sprays for spraying chemical on the sensitized face of the print while it is in position on the first roller, means for stripping the print from the roller including a water spray, the water spray being directed between the advancing print and the roller to wash the back side of the print, a second roller for receiving the print stripped from the first roller, a wash spray for stripping the print from the second roller and for washing the developed side of the print, a third roller for receiving the print stripped from the second roller, squeegee rollers positioned to roll on the roller and print to squeegee water from the print, and stripping means for stripping the print from the third roller.
10. In a print developing machine, a first and last roller mounted for rotation on parallel axes, means for feeding the print to the machine comprising roller means for propelling the print and supporting means for supporting it as it is being propelled, and water sprays for wetting the print to cause it to adhere to the first roller, other water sprays for washing the print, an intermediate roller for carrying the print from the first to the last roller, means for spraying chemical on the print, means for removing the print from the last roller comprising stripper members adapted to pass between the print and the roller, the position of the advancing edge of the print with reference to the strippers being such that the print falls downward from the last roller as it is stripped therefrom by reason of gravity, and means for carrying the print from the machine.
11. In a developing machine, a roller, means for causing a print to adhere to the roller, a squeegee roller adapted to roll on the first roller, the squeegee roller being positioned at one side of the first roller whereby fluid directed onto the

print is caused to form a puddle contacting the print between and above the line of contact of the rollers by reason of the rollers being in intimate contact with the face of the print.

12. In a developing machine, a roller, means for causing a print to adhere to the roller, a squeegee roller rolling on the first roller and located at one side thereof, and means for directing a fluid spray on the roller just in front of the squeegee roller whereby the spray fluid covers the face of the print as it rotates on the roller and whereby also the squeegee roller forms a puddle of fluid between the squeegee roller and the first roller to insure the fluid reaching all points on one face of the print.

13. In a developing machine, at least two rollers positioned one above the other, means for stripping prints from the upper roller, the rollers being positioned one above the other and the stripping means being located between the rollers so that when the print is stripped from the upper roller gravity acts to cause the stripped print to fall from the upper roller to the lower.

14. In a developing machine, a roller having a surface which holds moisture in order to hold fluid on the surface thereof, means for applying fluid to the surface of the roller, and means for controlling the film of fluid on the roller comprising a squeegee strip.

15. In a developing machine, a roller having a moisture holding surface to hold fluid on the surface thereof, means for applying fluid to the surface of the roller, means for controlling the film of fluid on the roller comprising a squeegee strip, and means for assisting the application of fluid to the roller comprising a squeegee roller.

16. In a developing machine, a plurality of rollers, means for causing a print to adhere to the rollers comprising wetting means for wetting the rollers, means including a water spray for stripping the print from one roller and causing it to adhere to the next roller, spray means for washing the print as it passes over the rollers, feed rollers for causing the print to be carried to the first roller, supporting means for supporting the print as it is directed toward the first roller, stripper means for stripping the print from the last roller, and belts for carrying the print out of the machine.

FRED DONTZEL, JR. 50
